UNITED STATES PATENT OFFICE.

CLARENCE H. BRUNNER, OF BROOKLYN, NEW YORK.

RAIL-JOINT.

1,078,247.

Specification of Letters Patent. Patented Nov. 11, 1913.

Application filed March 29, 1913. Serial No. 757,597.

To all whom it may concern:

Be it known that I, CLARENCE H. BRUNNER, a citizen of the United States, residing at Brooklyn, in the county of Kings, State of New York, have invented certain new and useful Improvements in Rail-Joints; and I do hereby declare the following to be a full, clear, and exact description of the invention, such as will enable others skilled in the art to which it appertains to make and use the same.

This invention relates to rail joints of the scarf type and has for an object to provide an extremely rigid rail joint which will dispense with the use of fish plates and like coupling devices.

A further object is to produce a rail joint which will positively hold the abutting rail ends against either vertical or lateral displacement relatively to each other.

A still further object is to provide a rail joint in which the abutting rail ends may be easily and quickly locked together and secured to the ties through the instrumentality of the usual spikes and without other securing devices.

With the above objects in view the invention consists of certain novel details of construction and combination of parts herein-
30 after fully described and claimed, it being understood that various modifications may be made in the minor details of construction within the scope of the appended claims.

In the accompanying drawing illustrating this invention:—Figure 1 is a plan view of a rail joint embodying my improvements. Fig. 2 is a side elevation. Fig. 3 is a cross sectional view on the line 3—3 Fig. 1. Fig. 4 is a horizontal sectional view on the line 40 4—4 Fig. 2. Fig. 5 is a perspective view of one of the rail ends. Fig. 6 is a perspective view of the other rail end.

Referring now to the drawing in which like characters of reference designate similar parts, the rail joint is shown to comprise abutting rail ends 10 and 11 which interfit at their meeting and produce a scarf joint. The rail ends are each formed identical so that the description of one will suffice for both. Each rail end has the ball 12 severed vertically as shown at 13 to the web, and the web thickened for a considerable distance in advance and in rear of the end 13 of the ball, the thickened web being cut away on one side to the longi-

tudinal axis of the rail whereby a tongue 16 is produced in advance of the end of the ball and a recess 17 is produced in rear of the end of the ball.

The top of the thickened portion of the web slopes downwardly from the side of the ball as shown at 19 and merges with the side edge of the base flange in the vertical side face 20. The top of the recess 17 slopes downwardly from the end of the ball as 60 shown at 21 rearwardly to the end wall 22 of the recess and terminates in the horizontal plane of the top of the adjacent vertical side face 20. The top 23 of the tongue 16 slopes downwardly and forwardly from 65 the ball to the end 24 of the tongue, terminating in the top of the adjacent vertical side face 20.

Formed in the inner longitudinal wall 25 of the recess 17 is a horizontal slot 26 which 75 opens through the side face 20 of the thickened portion of the web on the opposite side of the rail from the recess. Formed on the inner longitudinal wall 27 of the tongue 16 is a horizontal oblong lug 28 which is disposed in the plane of the slot 26 and is of 80 such extent as to project beyond the plane of the side face 20 of the thickened portion of the web on the opposite side of the rail from the tongue, where the lug is provided with 85 a longitudinal series of spike openings 29.

In assembling the rail ends 10 and 11, the rail ends are slid laterally toward each other so that the tongue 16 of one rail projects into the recess 17 of the other rail and the lug 28 of one rail projects through the slot 26 of the other rail, as best shown in Fig. 4. The lugs project upon opposite sides of the rails and are spiked to the underlying ties 30 through the instrumentality of spikes 31 95 passed through the spike openings in the lugs. The interfitting tongues as well as the lugs passing through their respective slots, positively lock the abutting rail ends against vertical displacement, while the lugs prevent 100 any longitudinal relative movement of the rail ends. Furthermore, the spikes positively prevent the rail ends moving apart laterally, so that a rail joint constructed as above described will positively hold the rails 105 against any relative movement whatever, while at the same time the joint will be extremely strong and rigid, and as is evident will not employ fish plates or other separate fastening devices.

What is claimed, is:—

1. A rail joint including abutting rail ends, each rail end being formed with a tongue projecting beyond the ball of the rail and fitting in a recess disposed in rear of the ball of the mating rail, a lug formed on the inner side of each tongue projecting through and beyond a slot formed in the inner wall of the recess of the mating rail, and securing spikes passed through said tongue.
2. In a rail joint, abutting rail ends, each rail end having the ball severed to the web, and having the web thickened in advance and in rear of said ball, one side of said thickened web being cut away to produce a tongue in advance of said ball and a recess

in rear of said ball end, a slot being formed in the inner longitudinal wall of said recess, a lug formed on the inner wall of said tongue in the plane of said slot, the tongue of one rail snugly fitting in the recess of the mating rail, and the lug of one rail projecting through the slot of the mating rail, said lugs projecting from opposite sides of said abutting rail ends, and securing spikes passed through said lugs.

In testimony whereof, I affix my signature, in the presence of two witnesses.

CLARENCE H. BRUNNER.
